UNITED STATES PATENT OFFICE.

EDGAR F. HATHAWAY, OF DORCHESTER, MASSACHUSETTS, ASSIGNOR TO SHAWMUT ENGINEERING COMPANY, OF DORCHESTER, MASSACHUSETTS, A CORPORATION OF MASSACHUSETTS.

PATTERN-CONTROLLED COUNTER MECHANISM FOR TEXTILE MACHINES.

Application filed November 10, 1916. Serial No. 130,673.

To all whom it may concern:

Be it known that I, EDGAR F. HATHAWAY, a citizen of the United States, and a resident of Dorchester, in the county of Suffolk 5 and State of Massachusetts, have invented an Improvement in Pattern-Controlled Counter Mechanism for Textile Machines, of which the following description, in connection with the accompanying drawings, is 10 a specification, like characters on the drawings representing like parts.

This invention relates to pattern controlled counter mechanism for textile machines and particularly to looms and more 15 especially to the shuttle box mechanism thereof.

In order that the principle of the invention may readily be understood, I have disclosed a single embodiment thereof in the 20 accompanying drawings, wherein—

Fig. 1 is a side elevation of the shuttle box shifting mechanism of a loom and pattern controlled counter mechanism therefor;

Fig. 2 is a side elevation of the pattern controlled counter mechanism shown in Fig. 1, upon a larger scale;

Fig. 3 is a front elevation of the mechanism shown in Fig. 2;

Fig. 4 is a section transverse the loom 30 taken through a portion of the mechanism shown in Fig. 3 and showing the parts in non-driving relation to the pattern member;

Fig. 5 is a section transverse the loom and taken through the mechanism shown 35 in Fig. 3;

Fig. 6 is a view similar to Fig. 5 but representing the parts differently positioned;

Fig. 7 is a plan view of the mechanism shown in Fig. 2;

Fig. 8 is a section transverse the loom taken through one of the counter elements, the pattern member and the interconnect- 40 ing means, on line 8—8, Fig. 7;

Fig. 9 is a detail in transverse section on line 9—9, Fig. 7 showing means to prevent over actuation of one of the counter elements;

Fig. 10 is a longitudinal section taken through the several counter elements;

Fig. 11 is a detail in perspective of one 50 of the parts shown in Fig. 9; and

Fig. 12 is a transverse section on the line 12—12 of Fig. 3.

In my co-pending application Serial No. 130,672 filed November 10, 1916, I have disclosed an organization involving the use of 55 counter elements of lower and higher order and pattern controlling means therefor, such organization being adapted for general application. The present invention is likewise 60 capable of general application but is peculiarly adapted to textile mechanism and more especially to looms. Herein I have disclosed an organization whereby a plurality of shifting shuttle boxes are governed through the 65 agency of inter-related counter elements and a pattern governing member or means therefor.

Without in any way restricting my invention to such arrangement of parts, I have 70 herein represented a loom having at one end thereof four shifting shuttle boxes and have provided two members capable of occupying four different relative positions, namely, either member up, either down, both members up and both members down. The position of said members determines which of the shifting shuttle boxes is brought to the level of the lay or into operative relation, and is determined by independently operated 75 counter elements, the functioning whereof is controlled by a pattern member, herein shown as an endless sheet. By employing counter members of lower and higher order and which may be of any desired denomina- 80 tion, it is evident that a vast number of changes may be effected or controlled in the 85 weft by a comparatively simple organization of parts.

In the mechanism herein disclosed, I provide a plurality of counter elements herein represented as disks, and which while they may be of any desired denomination, are herein shown as a five counter disk, a thirty counter disk, a hundred counter disk, a five 95 hundred counter disk and a thousand counter disk. In the loom herein shown and wherein shifting shuttle boxes are employed at one side only thereof, each impulse or movement of a counter disk corresponds to and 100 means two picks of a shuttle,—that is, across the loom and return. If therefore the thousand counter be brought into action by the call of the pattern, two thousand picks are thrown in, and thereupon the pattern func- 105 tions either to bring into action another

counter or to cause the repetition of the functioning of said thousand counter. In this manner, the pattern member or sheet may absolutely control the number of picks 5 and yet may itself be of short length and of simple construction.

Having made this brief explanation of the general purpose of the invention and of the organization by which such purpose is 10 herein effected, I will proceed to the description of that embodiment of my invention herein selected for disclosure.

In the drawings,—the frame of the loom is indicated at 1 in Fig. 1, and the shifting shuttle boxes generally at 2. Obviously, my invention may be employed in or in connection with a loom having shifting shuttle boxes at both sides thereof, but in the form of loom illustrated I have shown four shifting shuttle boxes A, B, C, D at one side of the loom only. The loom herein represented may be of the so-called Crompton and Knowles type. The said shuttle boxes are supported by a lifting rod 3, to the lower 15 end of which is connected a bracket 4 having attached thereto a link 5 to the upper end of which is pivoted at 6 one arm of the lever 7 itself pivoted at 8 in the framing of the machine and having its opposite end 20 pivotally connected at 9 to a link 10 operatively connected to some suitable part of the box shifting mechanism, as, for example, to a part or member connected with one of the shifting teeth of the shuttle box changing 25 mechanism. Also pivotally supported at 8 is a lever 11 to which is pivotally connected at 12 a link 13 also operatively connected to another part or member connected with the shuttle box changing mechanism, as for 30 example, another sliding tooth of such mechanism. These parts being of any suitable and usual construction, need not be more particularly described. The several positions assumed by said levers 7 and 11 35 result in bringing the shuttle boxes A, B, C, D to the level of the lay in any desired order. In order to impart selective movements to said levers 7 and 11, the link 10 may be operatively associated with a link 14 and the link 13 may be operatively associated with a lever 15, to which is pivotally connected at 16 a link 17. The links 14 and 17 40 extend in an upwardly inclined direction as indicated in Fig. 1 to and are pivoted or 45 otherwise suitably secured to two levers 18, 19, which as shown most clearly in Figs. 3, 5 and 7 are loosely mounted for swinging movement upon a stud or pin 20 mounted in a bracket 21 secured to the framing of 50 the loom. Each of said levers 18, 19 is of bell crank form and the lower arms 22, 23 thereof are adapted to be engaged by some suitable means so as in their movement to 55 control the position of the shifting shuttle boxes. In that form of my invention herein 60

shown, when both the levers 18, 19 remain unactuated or unlifted, and the arms 22, 23, thereof occupy vertical positions, then the shuttle box A is active. When the lever 18 only is lifted, the shuttle box B becomes active. When the lever 19 only is lifted, the shuttle box C is active, and when the levers 18 and 19 are both lifted, the shuttle box D is active. 70

Obviously this organization and arrangement may be widely varied within the scope and purpose of my invention. I contemplate the employment of inter-related counter elements and pattern controlling means therefor to effect the selection of said levers 18, 19 in accordance with the arrangement herein referred to, and the actuation of said levers in accordance with their selection. 75

For this purpose I have provided means, the selected embodiment of which is organized as follows:

Upon a shaft 24 fixedly supported in the machine frame I mount loosely a plurality of counter elements, preferably of disk form and which may be of any suitable denomination. Herein I have represented a five counter having a disk 25 and a ratchet 26 attached thereto; a thirty disk 27 having a ratchet 28 attached thereto; a hundred counter comprising two disks 29, 30, having 90 attached thereto gears 31, 32, respectively, with which mesh attached pinions 33, 34, upon a stud or pin 35, said hundred counter having an attached ratchet 36; a five hundred counter composed of two disks 37, 38, to 95 which are respectively attached gears 39, 40, with which mesh attached pinions 41, 42 upon said stud 35, and a ratchet 43 attached to gear 39; and a thousand counter composed of two disks 44, 45, to which are respectively 100 attached gears 46, 47, with which mesh attached pinions 48, 49, upon said stud 35, said thousand counter having a ratchet 50 attached to said gear 46. 105

The said several counter elements constructed as herein shown are of the general type shown in my said co-pending application and the teeth upon the ratchets thereof, and the teeth upon the gears thereof may be such as are necessary for the purpose of 110 counting selected numbers, and need not be particularly referred to. The several disks of the counter elements are provided with one or more slots according to the denomination of the counters, such slots being indicated at 51 in the several figures. When said slots are suitably brought into alignment or into such other relation as permits some associated part to move or function, then because of such relation of the slots 115 movement of the controlling pattern surface is permitted or effected. 120

As I did not in this application name the particular construction of the counter elements so far as the number of slots 51, the 125

number of teeth upon the ratchets and the capacity of each counter, are concerned, it is unnecessary to describe the same at length. In said prior application Serial No. 130,672, 5 I disclosed four counter elements, namely, units, tens, hundreds and thousands, the units counter being provided with ten slots, the tens counter with a single slot, the hundreds counter with ten slots in one part 10 thereof and a single slot in another part thereof, and the thousands counter being provided with a single slot in each of the two disks of which it is composed. In the present case while in no wise limited there- 15 to, I have disclosed fives, thirties, hundreds, five hundreds and thousands counters, although obviously the counters may be the same as in said companion case. The number of slots 51 and the number of teeth in 20 the ratchets pertaining to the counters differ in accordance with the capacity of the several counters and in order to obtain the differential movements necessary to the operation of the mechanism.

25 In Fig. 10 of the drawing, I have shown the fives counter, the thirties counter, the hundreds counter, the five hundreds counter and the thousands counter.

Each of said counters is provided with at 30 least one disk, the one hundreds, five hundreds and thousands being provided with two disks, and each disk has a cooperating ratchet. The number of notches in the several counters depends upon the counting ca- 35 pacity of the counter. For example, in the fives counter, there may be provided five notches, and in the thirties counter there may be provided thirty notches. The one hundreds counter may be provided with five 40 notches in each disk; the five hundreds counter may be provided with two diamet- rically positioned notches in each of its disks; and the thousands counter may be provided with a single notch in each of its 45 two disks. In those cases where the counters are made up of two disks, it will be under- stood that as already described the two disks are rotated at differential speeds, so as to bring two notches in the two disks thereof 50 into alignment at the proper time. For ex- ample, making reference to the two disks of the thousands counter, the gears thereof are provided respectively with ninety-nine and one hundred teeth, so that only once in 55 one thousand impulses are the notches brought into transverse alignment. The gears of the five hundreds counter may also have ninety-nine and one hundred teeth, the difference in result being due to the dif- 60 ferent arrangement and number of the notches. In other words, in the case of the one thousands counter, it will require one thousand impulses of the proper pawl to bring the two notches into transverse align- 65 ment, and in the case of the five hundreds

counter, it will require five hundred im- pulses of the corresponding pawl to bring two of the notches into transverse alignment, and in the case of the one hundreds counter, it will require one hundred impulses of the 70 corresponding pawl to bring two of the notches into transverse alignment.

The several counter elements, which, as previously stated, may be of any suitable construction, are mounted for independent 75 movement upon the shaft 24, and are individually actuated by means of suitable pawls 52, 53, 54, 55, 56, respectively imparting impulses to the five, the thirty, the hundred, the five hundred and the thousand 80 counters. The said pawls are loosely mounted upon a pin or stud 57 carried in the upper bifurcated arms 58 of a lever 59 mounted upon a rock shaft 60 suitably supported in the framing of the machine and having 85 movements of oscillation imparted thereto in any suitable manner.

For this purpose I have herein represented said shaft 60 as having fast thereon a gear 61 with which meshes a segmental rack 62 90 upon a lever 63 pivoted at 64 upon the framing of the machine. The said lever 63 is rocked in any suitable manner and for this purpose I have herein represented it as having a roll 65 extending into the cam 95 track 66 of a cam on shaft 67 vertically mounted in a suitable bracket 68 and having at its lower end a beveled pinion 69 meshing with and driven by a similar pinion 70 upon a shaft 71 which is preferably a half 100 time shaft or a shaft driven in about that time from the crank shaft 72, and herein by the gear 73 upon the shaft 71 meshing with a pinion 74 upon the crank shaft 72.

In this or in any other suitable manner, 105 movement is imparted to the shaft 60 so as thereby to impart impulses or movements of rotation to the several counter elements.

So long as any of the pawls 52, 53, 54, 55, or 56 is held out of engagement with its 110 ratchet, the corresponding counter element is inactive. I provide suitable pattern means of any suitable character controlling the functioning of said pawls. For the purpose I have herein provided a pattern sheet 75 115 which may be of metal or other suitable material and is preferably of endless form. The said pattern sheet may have suitable conformations controlling the functioning of the said counter elements, but herein for 120 the purpose and as most clearly shown in Fig. 2, I have formed said member 75 with a series of openings, herein arranged in five rows 76, 77, 78, 79 and 80 respectively controlling the five, the thirty, the hundred, the 125 five hundred and the thousand counter.

The pattern sheet 75 is supported for step by step movement upon a barrel 81 loose upon a shaft 82 mounted in suitable bearings upon the machine frame and capable of 130

manual rotation for the resetting of the pattern, as hereinafter described, through the agency of a knurled knob 83 at the end of said shaft, as shown most clearly in Figs. 5 2 and 7. A step by step movement of rotation is imparted to said barrel 81 in any suitable manner and preferably by means of a ratchet 84 fast or integral with said barrel and with the teeth 85 of which is 10 adapted at the proper time to engage a pawl 86 pivoted at 87 upon a lever arm 88 loosely mounted upon said shaft 82 and having its outer end pivotally connected at 89 to a link 90 to the outer end of which is 15 pivotally connected at 91 a lever arm 92 fast upon the rock shaft 60. In this manner each rocking movement of the rock shaft 60 in a clockwise direction, viewing Fig. 3, imparts a single impulse or movement of 20 rotation to the barrel 81 provided the drive pawl 86 be in driving relation to said barrel. The step by step movements of said barrel 81 are transmitted to the pattern sheet 75 by reason of teeth 93 upon opposite ends 25 of said barrel engaging openings 94 near the lateral edges of the said pattern sheet 75.

In this embodiment of my invention, the barrel 81 is not constantly driven in a step by step manner, but only periodically and 30 at times controlled by the functioning of one of the counter elements. I have previously stated that the several counter elements are each provided with one or more slots 51 and that when said slots are brought 35 into a certain predetermined relation, movement of the pattern surface is permitted. In the disclosed embodiment of the invention, the several slots 51 of the counter disks or elements are adapted to be brought 40 into alignment transversely of the machine upon the termination of the functioning of each counter element. That is to say, when the operation of the mechanism is begun, there is a transverse alignment of one slot 45 of each of the counter disks with a slot of each of the other counter disks. As impulses of rotation are imparted to any one of the counter disks, as for example, the thousand disk, it is evident that the notch 50 51 thereof is moved out of transverse alignment with the aligned slots of the other counter disks. This transverse alignment throughout the series of disks is not restored until one thousand has been counted 55 upon or by the said thousand disk which has been assumed to be the counter disk upon which counts are being indicated. When the said slot 51 upon said thousand counter disk is restored to said transverse alignment, 60 then through the operation of any suitable connections I effect movement of the pattern sheet 75 one step.

While for this purpose any suitable means may be provided, I have herein represented a bar 95 extending transversely of

the counter elements for the entire width thereof and adapted to enter the slots 51 when the same are brought into the described alignment. The said bar 95 is secured by one or more screws 96 to the upper 70 end of a lever arm 97 loosely mounted upon a stud 98 and normally inwardly pressed by a coil spring 99 surrounding a bolt 100 tapped into said lever arm 97 and extending loosely through a lug or projection 101 upon 75 the machine frame.

Also loosely mounted upon the shaft 98 and fast or rigid with the lever arm 97 is a lever arm 102 upon the inner or right hand end of which, viewing Figs. 3 and 4, is a 80 dog 103 pivoted at 104 and normally held in elevated position by a coil spring 105 interposed between said dog and the said lever arm 102. The driving pawl 86 is provided with a heel or projection 106. So long as 85 the bar 95 is held from entering the notches 51, that is, so long as it is in the position indicated in Fig. 4, then upon each rocking movement of the shaft 60 in a clockwise direction, the heel 106 of the pawl 86 is struck 90 by said dog 103 and is turned into inactive relation with the barrel 81 as shown in Fig. 4.

Therefore the pattern sheet 75 remains 95 unmoved until the slots 51 have been brought into transverse alignment and the bar 95 is permitted to enter them as indicated in Fig. 3. Thereupon the lever arm 102 is sufficiently rocked about the stud 98 to carry the dog 103 beneath the path of 100 movement of the heel 106 of the driving pawl 86 and therefore the barrel 81 is turned to the distance of one tooth by said driving pawl 86.

The barrel 81 is provided with a circumferential series of longitudinally extending grooves 107 permitting the entry through the openings in the pattern sheet 75 of certain vertically positioned feelers, which in the present embodiment of my invention are 110 seven in number, and are indicated at 108, 109, 110, 111, 112, 113 and 114 in Fig. 2. Two of said feelers, namely, 108, 109 cooperate as hereinafter described with the said levers 18, 19 and the remaining feelers 110 115 to 114 control the movements of the pawls 52, 53, 54, 55 and 56 of the counter disks.

Referring more particularly to Figs. 2, 3, 5 and 6, upon the stud 57 mounted in the forked upper lever end 58, 58, are loosely 120 mounted seven levers 115, 116, 117, 118, 119, 120, 121, which are controlled in position by the feelers 108 to 114, respectively. Each of said levers 115 and 116 is provided with a heel 122, to engage a lug 123 upon the 125 forked lever end 58 to prevent excess movement thereof. Above each of the levers 115 to 121, inclusive, and adjustably supported in the framing of the machine is a series of set screws 124, by which the swinging move- 130

ment of said levers may be adjustably limited.

In alignment with the depending arms 22, 23 of the levers 18, 19 are two slides 125, 126 mounted in suitable guiding portions 127, 128 of the machine frame and adapted to engage said depending arms 22, 23 in accordance with the call of the pattern and to elevate one or both of said levers 18, 19. 10 Each of said slides 125, 126 is notched as indicated at 129 to permit the engagement of the head 130, 131 of two dogs 132, 133 respectively. The said dogs are loosely pivoted upon a pin 134 in ears rising from the 15 guide 128 and each of said dogs is normally downwardly pressed by a spring 135, 136. Each of said dogs 132, 133 is provided with a downwardly extending heel 137, 138, and the relative location of the slides 125, 126 20 and the dogs 132, 133 is such that the levers 115, 116 will engage either said slides or said dogs according to the position of the feelers 108, 109. If, for example, the feeler 108 had entered a hole in the pattern surface 75, the 25 lever 115 engages the slide 125 and pushes it toward or to the left, viewing Fig. 5, thereby elevating the lever 18, thereby bringing the shuttle box B to the level of the lay. Thereupon the dog 132 enters the 30 notch 129 of said slide 125 and said slide is held in its advanced position, and consequently the said shuttle box B is maintained at the level of the lay (provided the lever 19 is not raised before the lever 18 is lowered) until the lever arm 115 is lifted by the rising movement of the feeler 108. When this occurs, said lever 115 strikes the 35 heel 137 of the dog 132 and lifts the same from the notch 129, thereby permitting the 40 slide 125 to move toward the right, viewing Figs. 5 and 6, which it does under the weight of the lever 18.

If while the slide 125 is held in its advanced position to the left, viewing Fig. 5, the slide 126 is similarly advanced, then the lever 19 is lifted and the shuttle box D is brought to the level of the lay. If the slide 125 is moved to the right and the slide 126 is moved to the left, then the shuttle box C 50 is brought to the level of the lay, and if both slides 125, 126 are moved to the right, viewing Figs. 5 and 6, then the shuttle box A is brought to the level of the lay.

It is evident that in this manner or in any 55 other suitable way, and by extensions of the mode of operation herein set forth, a large number of shuttle boxes may be controlled.

Each of the feelers 110, 111, 112, 113, 114 controls respectively one of the pawls 52, 60 53, 54, 55 and 56 in the manner indicated in Fig. 8. If one of said feelers 110 to 114 is lowered because the toe thereof enters an opening in the pattern sheet 75, then the corresponding pawl 52, 53, 54, 55, 56 is per-

mitted to drop into engagement with the 65 teeth of the ratchet controlled thereby, and the counter elements corresponding thereto receive an impulse of rotation.

Preferably I provide means for resetting to initial position each of the counter elements employed. For this purpose, I may provide any suitable means, and preferably the means shown in my said co-pending application. Herein for the purpose I have loosely mounted upon the stud 98 a lever 70 139 having two arms 140, 141. To the outer end of the arm 140 at 142 is pivotally secured a pin 143 extending up through an opening 144 in the framing of the machine and having a spring 145 coiled thereabout 75 and acting normally to press the arm 140 downward. Upon the arm 141 of said lever 139 is mounted the stud 35 whereon are loosely supported the several pinions 33, 34, 41, 42, 48 and 49, previously referred to.

The shaft 24 as most clearly shown in Fig. 8 is provided with a series of vertical slots 146 receiving therein pins 147 normally upwardly pressed by springs 148 and each having pivoted to its upper end at 149 a pawl 150 adapted to enter a notch 151 in the corresponding disk of the counter element. Said notches 151 are so positioned that rotation of the shaft 24 by the knurled nut 83, 95 after the lever 139 has been moved by projection 151' thereon to disengage the several pinions upon the stud 35 from the gears of said counter elements, causes the said counter elements to be turned until a slot 51 upon each of them is brought into register with the 100 bar 95.

It may occur with certain denominations of counters that the number of teeth upon the ratchet thereof are such that there is danger or liability of said ratchet being 105 moved the distance of two teeth by the pawl pertaining thereto. In the disclosed embodiment of my invention, wherein I have represented a thirty counter and have, as shown in Fig. 9, provided thirty teeth upon its 110 ratchet 28, I have secured a lug 152 upon the framing of the machine beneath the pawl 53 of said ratchet, and upon the under side of said pawl have formed a cam projection 153, which rides upon the lug 152, thereby holding the pawl 53 out of engagement with the teeth of the ratchet 28 until said cam projection 153 has passed to the left beyond said lug 152. Thereupon the pawl 53 drops into engagement with the teeth of the ratchet 28 120 and moves it the distance of one tooth only.

I may if desired provide any suitable means for effecting reverse rotation of the pattern sheet 75, as for example the means shown in my said co-pending application, but 125 which it is not necessary herein to disclose.

In Figs. 1 and 2, I have represented a coil spring 154, one end of which is attached to

the lever arm 88 and the other end to the pawl 86 and by which said parts are held in proper relative position.

Let it be assumed that the pattern surface 75 has been turned into such position as to present an opening beneath one of the vertically positioned feelers, such for example as feeler 108 in Figs. 5 and 6. Thereupon said feeler moves downward permitting the lever 115 to be brought into line with the slide 125. Upon the next movement of the lever 92, the slide 125 is moved forward, thereby rocking upward the lever 19 into the position shown in Fig. 5, and thus rendering the shuttle box B active (assuming that the lever 19 remains unlifted). In order to effect the turning of the pattern surface 75 into a position permitting the descent of the feeler 108, it is necessary to turn the independently operated counters until the notches 51 thereof are all in transverse alignment, whereupon the lever 102 carrying the pawl 108 fails to disengage the pawl 86 from the ratchet 84, 85, the result being that the said ratchet, and consequently the pattern surface are turned so as to present the proper opening to the said feeler 108.

In order to bring all the counters into such position that the needles 51 thereof are in transverse alignment, the proper pawls 52, 53, 54, 55, 56 are operated so as to impart the proper movement to the five, the thirty, the hundred, the five hundred and the thousand counters.

35 This sequence of operations is repeated with each change in the position of the shuttle boxes.

It will be evident from the foregoing description that I have provided means whereby the thread manipulating parts of a textile machine may be controlled through the agency of inter-related counting elements and pattern means. I have disclosed means whereby such inter-related instrumentalities are rendered effective to control the shifting shuttle boxes of a loom. My invention is, however, not limited in this respect, but is of broad application as herein before set forth.

50 Having thus described one illustrative embodiment of my invention, I desire it to be understood that although specific terms are employed, they are used in a generic and descriptive sense and not for purposes of limitation, the scope of the invention being set forth in the following claims.

Claims—

1. Pattern controlled counting mechanism comprising in combination, a plurality of independently operable counter members mounted side by side, cooperating pattern controlling means adapted to control said counter members, a plurality of parts each adapted to be moved into a plurality of positions and in each position to controlulti-

mately functioning members, governing connections between said pattern controlling means and said plurality of parts and a to and fro movable member for operating said counter member and said plurality of parts, 70 under the control of said pattern controlling means.

2. Pattern controlled counting mechanism comprising in combination, a plurality of independently operable counter members 75 mounted side by side, cooperating pattern controlling means adapted to control said counter members, a pair of levers each adapted to be moved into either of two positions, and thereby govern ultimately functioning 80 members, governing connections between said levers and said pattern controlling means and a to and fro movable member for operating said counter members and said pair of levers, under control of said pattern 85 controlling means.

3. Pattern controlling counting mechanism comprising in combination, a plurality of independently operable counter members, 90 cooperating pattern controlling means adapted to control said counter members, a plurality of movable parts each adapted to determine the selection of a functioning member independent governing connections 95 between said plurality of movable parts and said pattern controlling means and a to and fro movable member for operating said counter member and said plurality of parts, under the control of said pattern controlling means.

4. Pattern controlled counting mechanism comprising in combination, a plurality of independently operated counter members, 105 cooperating pattern controlling means adapted to control said counter members, and coordinating said counter members to represent a single predetermined number, a plurality of parts adapted to be moved into a plurality of functioning positions, a corresponding plurality of slides to act upon 110 said parts, and a corresponding plurality of feelers controlled by said pattern controlling means and adapted to control the movements of said slides respectively.

5. Pattern controlled counting mechanism 115 comprising in combination, a plurality of independently operable counter members, co-operating pattern controlling means adapted to control said counter members, and co-ordinating said counter members to represent a 120 single predetermined number, a plurality of movable parts each adapted to be moved into a plurality of positions to control functioning members, a corresponding plurality of slides to act upon said parts respectively, 125 means cooperating with said slides to hold or release them, means governed by said pattern controlling means to act upon said slides or upon said holding and releasing means according to the dictation of the pattern con- 130

trolling means and a to and fro movable member for operating said counter member and said plurality of parts, under the control of said pattern controlling means.

5. 6. Pattern controlled counting mechanism comprising in combination, a plurality of independently operated counter members, cooperating pattern controlling means adapted to control said counter members, and co-
ordinating said counter members to represent a single predetermined number, a plurality of levers each adapted to be moved into either of two positions, a set of slides to act directly upon said levers respectively, holding pawls for said slides respectively, a plurality of feelers governed by the pattern controlling means and members governed in position by said feelers and adapted to act upon said slides or said pawls according to
20 the dictation of the pattern controlling means.

7. Counting mechanism comprising in combination, a plurality of independently operated counter disks, a shaft whereon said disks are all mounted, cooperating pattern controlling means adapted to control said counter disks, a plurality of parts each adapted to be moved into a plurality of positions to control functioning members, a series of feelers controlled in position by the pattern controlling means, means controlled by said feelers to actuate said counter disks and said plurality of parts under control of said pattern controlling means, and a member to operate said means controlled by the feelers.

8. Counting mechanism comprising in combination, a plurality of independently operated counter disks, a shaft whereon said disks are all mounted, cooperating pattern controlling means adapted to control said counter disks and coordinating them to represent a single predetermined number, a plurality of parts each movable into a plurality of positions to control functioning members, a series of feelers governed in position by said pattern controlling means, a series of slides governed by certain of said feelers and themselves controlling the movement of said plurality of parts, and a series of counter disk operating members themselves controlled in position by others of said series of feelers.

9. Counting mechanism comprising in combination, a plurality of independently operated counter disks, a shaft whereon said disks are all mounted, cooperating pattern controlling means adapted to control said counter disks and coordinating them to represent a single predetermined number, a plurality of levers each adapted to be moved into two controlling positions, slides to act upon said levers, feelers governed by the pattern controlling means and themselves governing the position of the slides, operat-

ing means for the counter disks and feelers also governed by the pattern controlling means to govern the action of said counter disk operating means.

10. Counting mechanism comprising in combination, a plurality of independently operated counter disks, a shaft whereon said disks are all mounted, cooperating pattern controlling means adapted to control said counter disks and coordinating them to represent a single predetermined number, a plurality of levers each adapted to be moved into two controlling positions, slides to act upon said levers, feelers governed by the pattern controlling means and themselves governing the position of the slides, a series of pawls to move said series of counter disks, and a series of feelers for said pawls and governed by said pattern controlling means.

11. Counting mechanism comprising in combination, a plurality of independently operated counter disks, a shaft whereon said disks are all mounted, cooperating pattern controlling means adapted to control said counter disks and coordinating them to represent a single predetermined number, a pair of levers each having two positions, namely, an up position and a down position, a pair of slides to act upon and to control the positions of said levers, a pair of feelers to control said slides and themselves controlled in position by the pattern controlling means.

12. Counting mechanism comprising in combination, a plurality of independently operated counter disks, a shaft whereon said disks are all mounted, cooperating pattern controlling means adapted to control said counter disks and coordinating them to represent a single predetermined number, a pair of levers each having two positions, namely, an up position and a down position, and in said positions to control functioning members, a pair of slides to determine the positions of said levers and themselves controlled in position by said pattern controlling means.

13. Counting mechanism comprising in combination, a plurality of independently operated counter disks, a shaft whereon all of said disks are mounted, cooperating pattern controlling means adapted to control said counter disks, coordinating them to represent a single predetermined number, a ratchet for each counter disk, pawls for operating said ratchets, a plurality of parts each adapted to be moved into a plurality of positions to control functioning members, slides to operate said parts and members to operate said slides, said pawls and said slide operating members being under the control of said cooperating pattern controlling means.

14. Counting mechanism comprising in

combination, a plurality of independently operated counter disks, a shaft whereon said disks are all mounted, cooperating pattern controlling means adapted to control said counter disks and coordinating them to represent a single predetermined number, ratchets for said disks, pawls for operating said ratchets, a plurality of levers each adapted to be moved into a plurality of positions to control functioning members, a series of slides to determine the positions of said levers, and slide operating means, said pawls and said slide operating means being governed in action by the said cooperating pattern controlling means.

15. Counting mechanism comprising in combination, a plurality of independently operated counter disks, a shaft whereon said disks are all mounted, cooperating pattern controlling means adapted to control said counter disks and coordinating them to represent a single predetermined number, ratchets for said counter disks, pawls for operating said ratchets, a plurality of levers each adapted to be moved into a plurality of positions to control functioning members, slides to operate said levers and pushers to operate said slides, a movable part carrying said pawls and said pushers, said pawls and pushers being under control of said cooperating pattern controlling means.

16. Counting mechanism comprising in combination, a plurality of independently operated counter disks, a shaft whereon said disks are all mounted, cooperating pattern controlling means adapted to control said counter disks ratchets for said counter disks, pawls for said ratchets, a plurality of levers each adapted to be moved into a plurality of positions to control functioning members, slides to operate said levers, vertically movable feelers to govern the action of said pawls and said slides, said feelers being controlled by said cooperating pattern controlling means and a to and fro movable member to operate said slides and said pawls, under the control of said feelers.

17. Counting mechanism comprising in combination, a plurality of independently operated counter disks, a shaft whereon said disks are all mounted, cooperating pattern controlling means adapted to control said counter disks, ratchets for said counter members, pawls for operating said ratchets, a plurality of levers each adapted to be moved into a plurality of positions to control functioning members, horizontally movable slides to operate said levers, vertically movable feelers to govern the action of said pawls and said slides, said feelers being governed in action by said cooperating pattern controlling means and a to and fro movable member to operate said slides and said pawls, under the control of said feelers.

18. Counting mechanism comprising in

combination, a plurality of independently operated counter disks, a shaft whereon said disks are all mounted, cooperating pattern controlling means adapted to control said counter disks and coordinating them to represent a single predetermined number, a plurality of parts each adapted to be moved into a plurality of positions to control functioning members, a plurality of slides to move said parts, pawls adapted to engage said slides, means adapted to engage either said slides or said pawls and feelers controlling the position of said means to determine whether the slides or pawls shall be acted upon by said means, said feelers being under the control of said cooperating pattern controlling means.

19. Counting mechanism comprising in combination, a plurality of independently operated counter disks, a shaft whereon said disks are all mounted, cooperating pattern controlling means adapted to control said counter disks and coordinating to represent a single predetermined number, a plurality of parts each adapted to be moved into a plurality of positions to control functioning members, ratchets for said counter members, pawls for operating said ratchets, a plurality of levers each adapted to be moved into a plurality of positions to control functioning members, slides to operate said levers, pawls to engage and hold said slides, pusher means to engage said slides or pawls, and feelers adapted to engage said pusher means and said pawls for the ratchets, said feelers being governed by the operating pattern controlling means.

20. Counting mechanism comprising in combination, a plurality of independently operated counter disks, a shaft whereon said disks are all mounted, cooperating pattern controlling means adapted to control said counter disks and coordinating them to represent a single predetermined number, a plurality of horizontally movable slides to operate said plurality of parts, a corresponding plurality of pawls overlying said slides and adapted to engage them, a corresponding plurality of pusher members to engage said pawls or slides and vertically movable feelers to determine the position of said pusher members, said feelers being under the control of said cooperating pattern controlling means.

21. Counting means comprising in combination, a plurality of independently operable counter disks arranged side by side and having notched peripheries which may be brought into a transverse alignment, a part adapted to enter said notches when in transverse alignment, cooperating pattern controlling means adapted to control said counter disks and itself controlled in operation by said notch-entering controlling part, a plurality of parts each adapted to

- be moved into a plurality of positions to control functioning members, a series of feelers controlled in position by the pattern controlling means, means controlled by said 5 feelers to actuate said counter disks and said plurality of parts under control of said pattern controlling means, and a member to operate said means controlled by the feelers.
- 10 22. Counting means comprising in combination, a plurality of independently operated counter disks having notched peripheries which may be brought into transverse alignment, a part adapted to enter said notches when in transvers alignment, cooperating pattern controlling means adapted to control said counter disks and coordinating them to represent a single predetermined number and itself controlled in operation by said notch-entering controlling part, a plurality of levers each adapted to be moved into a plurality of positions to control functioning members, a corresponding plurality of slides to operate said plu- rality of parts, and a corresponding plurality of feelers to control the operation of said slides, said feelers being governed in position by said cooperating pattern controlling means.
- 15 23. Pattern controlled counting mechanism comprising in combination, a plurality of independently operable counter members, cooperating pattern controlling means adapted to control said counter members, a plurality of parts each adapted to be 35 moved into a plurality of positions and in each position to control ultimately functioning members, governing connections between said pattern controlling means and said plurality of parts, and a to and fro 40 movable member for operating said counter members and said plurality of parts, under the control of said pattern controlling means.
- 20 In testimony whereof, I have signed my 45 name to this specification.

EDGAR F. HATHAWAY.
